UNITED STATES PATENT OFFICE.

RICHARD C. HILL, OF PHILADELPHIA, PENNSYLVANIA.

DESIGN FOR A BUTTON.

SPECIFICATION forming part of Design No. 35,026, dated September 3, 1901.

Application filed July 6, 1901. Serial No. 67,369. Term of patent 7 years.

To all whom it may concern:

Be it known that I, RICHARD C. HILL, a citizen of the United States, residing at 2402 Montgomery avenue, (care of S. Galton Reilly,) Philadelphia, in the county of Philadelphia and State of Pennsylvania, have invented a new and original Design for a Button, of which the following is a specification, reference being had to the accompanying drawing, forming a part hereof.

The drawing represents a perspective view of my new design for a button.

The design for a button discloses a disk-shaped base 1, of concavo-convex form, at one side of which is arranged a similar disk-shaped head 2, and the said head and base are located at suitable distance from each other by an interposed shank 3, which embodies diverging portions 4, which are connected at one end to the head 2 and which diverge therefrom toward the base. Upon approaching the base 1 the diverging portions of the shank are extended in opposite directions, so as to bear a radial relation to the base and so as to terminate at the periphery

or rim of the base, as clearly illustrated in the drawing. Encircling the shank 3 is a spiral coil 5, one extremity of which is bent at an angle, as shown at 6, so as to meet the peripheral edge of the base. The coil extends spirally from such point around the shank 3 and has its extremity bent or recurved, as shown at 7, to form a slightly-enlarged rounded and blunt end. The spiral coil while encircling the shank 3 is interposed between the base and head and is located nearer the base than the head.

The leading or material features of the design reside in the spiral coil interposed between the head and base in connection with the shank, having diverging portions which are encircled by the spiral coil.

I claim—

The design for a button as herein shown and described.

RICHARD C. HILL.
